(57) **CLAIM**

The ornamental design for a sealing assembly for mating an electrical device enclosure, as shown and described.

DESCRIPTION

FIG. 1 is an exploded perspective view of the sealing assembly for mating an electrical device enclosure employing my new design;

FIG. 2 is a top view of FIG. 1;

FIG. 3 is a perspective partial assembled view of FIG. 1;

FIG. 4 is a top view of the assembled sealing assembly of FIG. 1;

FIG. 5 is a bottom view of the assembled sealing assembly of FIG. 1;

FIG. 6 is a right side view of the assembled sealing assembly of FIG. 1;

FIG. 7 is a left side view of the assembled sealing assembly of FIG. 1;

FIG. 8 is a rear view of the assembled sealing assembly of FIG. 1; and,

FIG. 9 is a front view of the assembled sealing assembly of FIG. 1.

The broken lines showing portions of the article are included for the purpose of illustrating environmental structure and form no part of the claimed design.
